UNITED STATES PATENT OFFICE.

JOSEPH A. GROEBLI, OF NEW YORK, N. Y.

JACQUARD MECHANISM.

1,073,343.

Specification of Letters Patent. Patented Sept. 16, 1913.

Application filed November 25, 1911. Serial No. 662,277.

To all whom it may concern:

Be it known that I, JOSEPH A. GROEBLI, a citizen of the United States, and a resident of the city, county, and State of New York, have invented certain new and useful Improvements in Jacquard Mechanism, of which the following is a specification.

My invention relates to a jacquard mechanism or automat, and while there may be other uses for the same, it is of particular advantage in the embroidering art as a means for automatically positioning the tambour frame for the different stitching operations.

My invention relates to what is generally known as an automat or jacquard wherein the various operations which effect the positioning of the tambour frame of an embroidery machine are automatically controlled by means of a jacquard card or pattern roll which usually consists of a long strip of paper provided with a number of apertures or perforations, the positions of which on the card, determine the various operations of the jacquard and therefore the movements of the tambour frame of the embroidery machine.

The tambour frame must be moved in a great number of different directions and extents in order that the stitching mechanism will produce the various stitches which compose the design, upon the fabric: and in United States Letters Patent No. 528632, dated November 6, 1894, I showed and described in detail a complete jacquard for operating the tambour frame of an embroidery machine, wherein, by the use of a comparatively small number of slides (twenty-eight being shown in said patent) and by the combining, in a novel manner, various movements of different extents the tambour frame of an embroidery machine is caused to move in many different directions in its vertical plane of movement and to move many different units in extent. In the jacquard there are shown 28, different needles or feelers which coöperate with the pattern roll or jacquard card and are either advanced by striking the jacquard card when the latter is oscillated, or remain stationary if they happen to lie in line with a perforation, as the case may be. Each such needle or feeler is there arranged to operate a definite slide or selector and the slides in turn operate to select and combine devices for producing different units of motion, so that the tam-

bour frame of the embroidering machine will be moved according to the resultant of such units of motion, thereby reducing the number of slides necessary to produce a great number of movements. In that machine as just stated, there are 28, feelers or needles for controlling the positioning movements, in addition to various other needles, and such needles are arranged in a horizontal row, laterally of the jacquard card, and each needle is represented by a position on the jacquard card. The perforations are arranged on the jacquard card in transverse rows and in each row the perforations may come in line with any of the 28 needles just referred to, so that there may be said to be 28, positions on the jacquard card for the positioning needles. In that form of jacquard there are never more than four such perforations in a transverse row but those four may come at any four of the twenty eight positions. The needles and their slides are there arranged in four groups of seven each and only one in each group is operated at a given operation of the machine, but each of the four perforations may come in any of seven different positions. It will therefore be apparent that in a machine of the type referred to the jacquard card must be made wide enough for the twenty eight slides (when the number of elements are as there shown) in addition to such slides as are necessary for special purposes, such as for determining the direction of movement of the tambour frame moving devices etc. There are in that machine twenty-eight needles controlling the frame movements and therefore the jacquard card is wide enough to control all of these as well as various special needles.

An important object of my present invention is to make it possible to reduce the lateral dimension of the pattern roll or jacquard card by reducing the number of elements which are directly controlled by the jacquard card by contact therewith and to so arrange the mechanism that the same results may be obtained through this reduced number of elements. Referring to numbers of elements just for illustration I would say that under my present invention I am able to secure the same results by using only twelve needles or feelers, as is obtained by using twenty eight in said patent, reference being had to the needles which deter-

mine and combine the units of motion. It will be apparent therefore that the jacquard card may be of less width in order to operate the reduced number of needles or feelers.

The above is only stated as an instance, the number of parts being determined by the particular jacquard mechanism to which my present invention is applied. I accomplish this result by providing a very positive mechanism wherein the needles are preferably arranged or considered as groups and by causing a number of combinations in each group, the several groups will accomplish the same results as before with fewer needles in each group. For instance, let us consider a group of needles or feelers as consisting of three, there being four such groups in a jacquard of the type shown in my said patent. Each needle in a group not only controls a given unit of motion, but two or three needles in a group may be simultaneously operated and their action combined before the selection of the jacquard slides or selectors is effected. For instance, let needle *a*, represent one unit of motion, needle *b*, two units of motion and needle *c*, four units of motion. By operating needle *a*, the tambour frame will be moved one unit of motion: by operating *b*, two units of motion: by operating *c*, four units of motion: by operating *a* and *b* (and combining their action) three units of motion: by operating *a* and *c*, (and combining their action) five units of motion: by operating *b* and *c*, (and combining their action) six units of motion: and by operating *a*, *b*, and *c*, and combining their action, seven units of motion. Thus by using three slides in a group and having them represent 1, 2, and 4 units and operating them singly or conjointly, and in the latter case combining their action, I can produce the same results as where seven were used in my said patent, each representing a different unit, but operated only individually. It is to be understood that numbers of parts are here given only as an example and this is true throughout this case, but it is to be understood that by having more than three needles in a group a different number of combinations may be secured.

The above results may be obtained without increasing the number of parts throughout the jacquard, such as the jacquard slides or selectors, for the above results may be obtained in a jacquard such as is shown in my said patent without changing the number of jacquard slides.

While my invention is not limited in its application to one form of jacquard, I prefer to simplify the present case by showing my invention embodied in a jacquard like the one shown in my said patent because it is only necessary to substitute my present mechanism for a small part of the mechanism shown in said patent, the greater por-

tion of which latter may be here used without change.

The above results are obtained by employing a number of elements which are commonly known as droppers, there being as many droppers as there are jacquard needles controlling the extent of movement of the tambour frame of the embroidering machine. These droppers are adapted to be operated by the needles or feelers and each dropper in a group is arranged to cause a movement of a different extent in a selecting device which selects the jacquard slides or selectors for action: and any two or more droppers in a group may be operated to cause movements in the selecting device which will be the equivalent of the combined action of the several droppers so operated. The operation of the droppers, their action singly and combined, and the action of the selecting device which selects the slides, is all accomplished in a simple and positive manner and all conflict is positively avoided.

In the drawings forming a part of this application; Figure 1, is a longitudinal section of a jacquard mechanism showing the application of my invention, which corresponds with Fig. 5, of my former patent, Fig. 2, is a diagrammatic view showing the arrangement of jacquard slides, and it corresponds with Fig. 43, of my said patent, Fig. 3, is an end elevation of my present mechanism, with parts broken away, and is taken at right angles to Fig. 1, Fig. 4, is a side elevation, Fig. 5, is an elevation of the device for operating the selecting and slide-operating pins, Figs. 6, and 7, are sectional views through the main shaft, showing cams and levers for operating certain parts of the mechanism, and Fig. 8, is a plan view of a portion of the jacquard card.

The greater part of my said Patent #528632 may be used in connection with my present invention to constitute a complete jacquard and as the jacquard therein described is the best mechanism known to me for its purpose, I will describe my present invention as embodied in that form of machine. However, this is only to simplify the present case, and it will be apparent from the description of my invention that it is not limited to this particular adaptation.

In order to set forth clearly and in simple manner, the nature and working of my present invention it is preferable to refer in some respects to the number of parts in some branches of the device but I wish to state that my invention is not limited to a structure having any particular number of parts, as the number will depend partly upon the character of the jacquard to which my invention is applied. To make myself more easily understood, therefore, I will describe my invention as applied to a jacquard like

that shown in my said patent in which the number of jacquard slides and various other elements are as there shown. My present invention when applied to such a jacquard construction is substituted for some of the parts of that construction and in other respects it is supplemental thereof.

In Fig. 1, I have shown many of the parts of the jacquard referred to, but with some parts of my present invention superseding some of the elements of the former construction and a comparison of this view with Fig. 5, of said patent will make it apparent that, from the rods which operate to couple the various sliding frames down to and including the tambour frame I may, and preferably do, utilize the same elements as are shown in said patent. I have shown in the present case a jacquard from the card mechanism to the sliding frames and coupling devices, and considering the remainder of the machine as constructed in accordance with said patent a complete jacquard will be understood therefrom.

I have shown the supplemental shaft 2, (Fig. 1) as provided with the lever 3, wherein movements of varying extents originate; and it is by combining the various units which originate here, in various combinations that the embroidering machine tambour frame may be moved any desired extent or direction. The present invention relates more particularly to the devices which perform the functions of selecting these movements of various extent, determining the direction and the like.

The lever 3, has connected thereto a number of links 4, at various points along the lever, so that as the lever is oscillated the links will be reciprocated different extents according to the different arcs in which the point of connection of the links and lever travel. Each link is connected with a sliding frame 5, corresponding to the sliding frames G', etc., of my said patent; from which it will be understood that the sliding frames are reciprocated different units in extent, the number of units being seven in the example shown.

There are shown the prongs 6 of four sliding frames arranged in a horizontal plane and these correspond to the frames m to m^3 of my said patent and are for the same purpose. From these frames to the tambour frame of the embroidering machine I preferably utilize the mechanism shown in my said patent. By coupling the several frames 5 with the prongs 6, different combinations of movements are effected and the principal purpose of the card mechanism and associated parts is to effect these combinations. The several rods 7, are provided with locking pins for locking the various frames 5, with prongs 6, so that the latter will be operated according to the movements produced

in the former: and these locking bars and their pins are arranged similar to, and operate the same as, the locking bars k' of said patent and a detailed description thereof is not necessary here.

For controlling the interlocking and similar devices I preferably employ jacquard slides or selectors and preferably arrange them in the same order as in said patent, but certain modifications are made in the slides and their operation to adapt them to other branches of my invention as will appear hereinafter.

I will pass to a description of the elements first affected by the jacquard card and follow down to and including the slides.

In Fig. 3, I have shown a pair of rollers or idlers 8, which guide the pattern roll or jacquard card, 9, while the latter is traversing the reticulated pattern roller 10. The pattern engages around the pattern roller 10, and the latter is provided with regularly spaced bars 11, forming intermediate spaces 12 for the entry of the jacquard needles or feelers while the bars form a backing for the card on each side of the row of needles. This roller is in all respects like the roller E², of my said patent and is intended to be operated in the same manner and by the same mechanism as the roller of my said patent: but the roller in the present case is preferably arranged in a position at right angles to the roller shown in said patent. As stated, this roller is operated in the same manner and preferably by the same devices as in said patent, except as to the direction of its oscillations. The roller is partially revolved after each operation of the machine in the same manner as in said patent, but as I prefer to have the needles which operate the droppers engage the card from

above I oscillate the card roller up and down instead of horizontally. On the main shaft 1, of the machine I have arranged a cam 13, in the groove of which travels a bowl 14, on a lever 15^a. Another arm 15^b of said lever is connected by the link 15 to the lever 16. The lever 16, is fulcrumed on a stud 17, suitably supported. The forward arms 18, on the shaft 17, carry the shaft 19, of the card roller. At each revolution of the main shaft the cam 13, oscillates the lever 15^a, 15^b, and through the link 15, arm 16, shaft 17, and arms 18, the card roller is moved first upwardly and then downwardly.

Above the card roller and arranged above the stopping positions of the slots 12, of the card roller I have provided a number of jacquard needles or feelers which are intended to be engaged by the jacquard card when the card roller is oscillated, in case the needles are in line with a part of the card, or to be left in their lower position if they come opposite an aperture therein. The grouping and arrangement of the

needles will be better understood by reference to Fig. 4. It will be noted that there are four groups of needles of three in each group, numbered respectively 20, 21, and 22, 5 all in a horizontal line. Needles 20, 21, 22, on the right form one group, needles 20, 21, 22, adjacent thereto form a second etc. These are the needles which control the slides which in turn operate to cause or combine the movements of different extent that originate at the lever 3. They may be considered as the movement controlling needles. At the left of each group of movement-controlling needles (relative position is only 10 preferable) I have arranged one additional needle 23, 24, 25, 26, making four in all. These needles control the directional slides or those which determine whether the tambour frame moving elements shall be moved 15 to the right or left as the case may be. The needles 20, 21, 22, control the extent of movement, and the needles 23, to 26, the direction of movement of the elements which position the tambour frame. There are, therefore, 20 25 30 35 40 45 50 55 60 65 70 75 80 85 90 95 100 105 110 115 120 125 130

The several needles are guided in holes in the guide plates 27, arranged one above the other. Each needle of the movement-controlling groups is connected with a dropper. The needles 20, are each connected by a thin and flexible strap 28, with a dropper 29, which latter may be considered as representing one unit of motion in the selecting device. The needle 21, is connected also by a thin flexible strap 28, with a dropper 30, arranged behind the dropper 29, and being broader than dropper 29, may be considered as representing two units of motion in the slide selecting device. Also the needle 22, is connected by a thin strap 28, with a third dropper 31, which being wider than both 29, and 30, may be considered as representing four units of motion in the slide selecting device. As the needles are arranged in a row at right angles to the droppers, I have offset the straps 28, to bring them to the droppers one behind the other according to the positions of the droppers. This arrangement of droppers is duplicated for each of the four sets of needles, making in the instance given twelve droppers in four groups of three in each group. Such a group is shown in Fig. 3. From this it should be understood that only the needles controlling the extents of movements of the tambour frame are connected with droppers.

The several groups of droppers lie between the two guide plates 32, and 33, so 65 that the droppers may be moved vertically,

and they may also be moved horizontally, but preferably always within the confines of these plates. Each group of droppers is further confined to the proper place by small plates 27^a arranged transversely between the guide plates 32 and 33. 70

In line with each group of droppers is an engaging element, here shown as rods 34, 35, 36, 37, which reciprocate toward and from the droppers in apertures 38 in the plate 33. 75 As there are four groups of droppers I have shown four such rods arranged in a horizontal row, one rod in line with each group of droppers. These rods are fulcrumed respectively, to levers 39, 40, 41, and 42 and the latter fulcrum respectively on shafts 43, secured to the supporting plate. 44. Each of the shafts 43, is provided with an arm 45, to which one end of the coil springs 46 are connected, the other ends being secured to ears 47, on the plate 44. The purpose of these connections and springs is to draw the several rods 34 to 37 toward their respective groups of droppers, independently. To move the rods away from 80 their droppers also to permit them at the proper time to move against the droppers I have provided means which operates simultaneously on their several levers. I have provided an arm 48, which fulcrums on a shaft 49, on the plate 44: and beyond the several levers 39 to 42 I have provided a lever 50 which fulcrums on a shaft 51. One arm of this lever 50 and the upper end of arm 48 are united by a link 52 which latter 85 is provided with the four studs or pins 53, which project laterally thereof and engage respectively on one side of each of the several levers 39 to 42, so as to cause the return of the several levers in opposition to their 90 several springs. One arm 54, of the lever 50, is connected by a link 55, with an arm of a lever 56, which fulcrums on a stud 57 suitably supported. The other arm of the lever 56, has a bowl 58, which travels in the 95 groove of a cam 13 arranged on the main shaft of the machine. At each operation of the machine the cam 13, causes the lever 50, to be rocked, first to the left in Fig. 3, to permit the levers 39 to 42, to be drawn over 100 by their springs 46, and then to the right to positively return said levers. 105

In said Fig. 43, of my said patent I showed, diagrammatically, the arrangement of the various slides, including extent, directional and unlocking slides, and in Fig. 2, herein I have shown the arrangement of slides diagrammatically, from which it may be seen that the arrangement is somewhat similar except for the slides which control the unlocking devices and the directional slides. Herein there are four groups A. B. C. D. of slides arranged parallel, and each group consists of slides a, b, c, d, e, f, g, h, respectively, thus making eight slides in 110 115 120 125 130

each group, seven of which *a* to *g* represent different units of motion and slide *h* in each group is the locking slide. There are also four slides *E*, arranged beyond the 5 above groups and these control the directional elements. There are still other slides connected with the above mentioned slides. To the left in Fig. 2, it will be observed that there are seven groups of slides *A'*, *B'*, 10 *C'*, *D'*, *E'*, *F'*, *G'*, each having four slides *a'*, *b'*, *c'*, *d'*, slides *a* in each of the groups *A*, *B*, *C*, *D*, above referred to are connected by rods 60 each with a slide in group *A'*: slides *b* in each of the groups *A*, *B*, *C*, *D*, 15 are connected each with a slide in group *B'*, slide *c* in each group with a slide in group *C'*, etc., throughout to slide *g*. The slides *A'*, *B'*, *C'*, *D'*, *E'*, *F'*, *G'*, correspond with the slides *G* to *G'*, of my said patent. Be- 20 sides the above there is a group *H'* of slides containing four *i*, *j*, *k*, *l*, and to each of these is connected by a rod 60, the slides *h*, of the groups *A*, *B*, *C*, *D*. The group of slides *H'* corresponds with the slides *G*⁶⁰, of my said 25 patent and control the elements which lock the rack frames shown in said patent which are not to move upon any given operation of the machine. There is still another group of slides *I'* containing four slides, *m*, *n*, *o*, *p*, 30 which are connected by rods 60, with the four slides in group *E*. These correspond with slides *1^a*, in my said patent and are adapted to perform the same functions as the latter slides, and through the same 35 mechanism. They control the direction of rotation of the four pinions actuated by the rack frames.

From the above it will be apparent that I have provided slides for performing all the 40 operations performed by the several slides in said patent, but I have arranged them differently for convenience except the ones marked "shuttle", and "stopping" in said patent and they require no change. It will be noted 45 that each of the levers 39 to 42, is provided with a pin or plunger 61, which are movable laterally of the levers in transverse holes in the hubs 62^a. These pins are arranged to engage the ends of the several slides in the 50 groups *A*, *B*, *C*, *D*, to push the slides. The lever 39 has a movement sufficient to cause the pin 61, therein to come in line with any one of the slides in group *D*. In similar manner the pin 61, on lever 40, may be brought 55 into line with any slide in group *C*; pin 61, on lever 41, may be brought into line with any slide in group *B*; and pin 61, on lever 42, may be brought into line with any slide in group *A*. I have provided means between 60 the levers 39-42 and the several groups of slides for guiding the pins 61. I have mounted opposite the ends of the several slides a plate 62, which is provided with as many apertures 63, as there are slides in 65 groups *A* to *D*, and in line with such slides.

Eight of these apertures are arranged in the arc traversed by the pin 61, on lever 39, eight in the arc traversed by the pin on lever 40 and in the same way for the pins on levers 41, and 42. These apertures are countersunk at 64, on the side of the plate to- 70 ward the levers.

The means for reciprocating the pins 61, is as follows: Each pin 61, has a grooved engaging head 65, which straddles the plate 66, and these heads are adapted to move along the plate 66, and in their respective arcs. The plate 66, is carried upon arms 67, which are arranged to move the plate 66, for the purpose of moving the pins 61, to- 75 ward and away from their several slides. The arms 67, are secured to shafts 68, suitably supported, and one of them forms part of a lever. The other arm 69 of this lever is connected by a link 70, having a slot 71; 80 to a lever 73. The latter is fulcrumed upon a suitably supported stud 74, and one arm thereof has a bowl 75, which travels in contact with a cam 76, on the main shaft. At each operation of the machine the rise of 85 lever 73, permits the spring 77, to draw the arms 67, and plate 66, to the left in Fig. 4. This causes the pins 61, to contact with and push whichever of the slides they are in line with at the time. The return of the pins 61, 90 is caused, positively, by the cam 76, acting on lever 73. The needles 22', are connected by the rods 23, 24, 25, 26, with the levers 78, there being four such levers arranged side by side and fulcruming on a shaft 79. 95 Through these connections the four slides *E*, shown in Fig. 2 are operated to control the direction of movement of the rack frames of said patent. The upper arms of the levers 78, each engage in a slot 80, in the slides *E*. 100 (see Fig. 4).

All the slides shown in the right half of Fig. 2 are preferably alike, except that only the slides in group *E*, have slots for the levers 78. The slides are guided in slots 81, 110 in the four guide plates 82, which permit of longitudinal movement only, of the several slides. The slides are preferably formed of straight plates instead of being T-shaped and each slide is connected by a rod 60 as previously stated with some slide on the left half of Fig. 2, similar to the arrangement shown in said patent. On the upper edge of each slide I have provided the two notches 83 and 84 one just behind the other. On a shaft 85, I have secured two arms 86, to which is attached a V-shaped bar 87, which is arranged to engage in the notches 83, of those slides which are advanced upon an operation of the jacquard card; and in the 115 notches 84, of those which are not advanced, but are left in their original position. A spring 88, connected with the arm 89, and the plate 82, tends to draw the end 87, of the arm 89, into the notches of the several slides, 120 125 130

while at regular intervals the spring is overcome and the arm is disengaged from the slides. The arm 89, of lever 86, is connected by a link 90 with a lever 91, which fulcrums on a stud 92. Another arm of lever 91, has a bowl 93, which engages with a cam 94, on the main shaft so that periodically the lever 86, will be rocked to lock and unlock the several slides. The arm 86, performs a similar function to the arm O' of my said patent.

The slides are preferably only advanced by the pins 61, and returned by separate mechanism. Levers 95, are mounted on a shaft 96, (see Fig. 4) and to said arms is secured a bar 97, extending across in front of one end of the several slides A, B, C, D, and E. An arm of the lever 95, is connected by a link 98, with a lever 99, rocking on a stud 100. This latter lever has a bowl 101, traveling in a groove in the cam 76, on the main shaft. The periodical rocking of lever 95, first to the left in Fig. 4, and then to the right, first permits the slides in Fig. 2, to be advanced and the lever 95, positively returns all of them upon the return movement of the lever. Passing now to the slides shown in the left in Fig. 1, it will be noted that they are somewhat similar to the corresponding slides in said patent. On their rear end they are curved at 103, so as to rock thereon as a fulcrum and are guided by the grooved plates 104. For each of the slides in the left of Fig. 2, there is provided a plate 105 which plates correspond to, and operate the same mechanisms as the plates k, of said patent. That is, some control the rods coupling up movements of different extent, others control the direction of movement and still others control the locking of the rack frames which are not to be moved. Their function and operation may all be understood from said patent.

The several slides last referred to serve to raise the plates 105, or hold them down, as the case may be, and for this reason the plates 105, have pins 106, between which the slides engage. The forward ends of the slides are somewhat modified. There is a recess at 107, on the lower edge of each slide, and a recess 108, on the upper edge, and behind the first one. To shafts 109 and 110 are secured respectively the arms 111, and 112. On the arms 111, is carried the plate 113, while on the arms 112, is carried the plate 114, the former being slightly in advance of plate 114, which is a reversal of the condition shown in said patent. To a shaft 115, are secured arms 116, which carry a bar or plate 117, which is arranged to engage either of the slots 118, in the several plates 105, for the purpose of locking the latter in either their raised or lower positions, and this corresponds with the plate 65 M^o, in said patent.

The purpose of the plates or jaws 113, 114, is to raise those plates 105, the slides of which are advanced or moved to the left in Fig. 1, for the purpose of operating the various locking rods 7, the same as in my said patent. Owing to the shape of the ends of these slides and the relative positions of the jaws 113, 114, there will be a reversal of the action over that of my said patent. That is, the slides which remain forward or are not moved are engaged by the lower jaw 114, acting in the recess 107 and the upper jaw engaging on the edge 119. The slides so engaged will be retained in the lower position. Those slides which are reciprocated are the ones which cause active movements and they will be so moved that the jaw 114, will engage the slides so moved, at 120, while the upper jaw 113, will be in line with the recess 108, and consequently the slides thus affected will be raised when the jaws are closed and their respective plates 105, will be raised to operate the locking bars 7, and associated elements. In my said patent the slides which remain in the forward position determine the operation of the machine, or are properly considered as the controlling slides in each operation, whereas in the present structure, the slides which are advanced are preferably the ones which are the active ones, or control the operation of the locking elements; and hence the reversal of the shape of the ends of the slides and the jaws 113, 114. In Fig. 4, I have shown means for rocking shafts 109, 110 similar to that shown in my said patent.

On shafts 109, and 110 are provided, respectively, the arms 121, 122, and directed in opposite directions from their shafts; and they are fulcrumed to the bifurcated ends of a link 123. The lower end of this link connects with a lever 124, which rocks on a fixed stud 125, and an arm of this lever has a bowl 126, which travels in the groove of a cam 94 on the main shaft. Each revolution of the cam 94 with the main shaft causes the lever 124, to rock, and through the link 123, the arms 121, 122, are rocked in reverse directions. Consequently the shafts 109, and 110 will be rocked and the jaws 113, 114, will move toward and away from each other as they do in my said patent.

On the shaft 115, there is an arm 128, (see Fig. 4) which is connected by a link 129, with lever 91, rocking from a fixed fulcrum 92. An arm of this lever has a bowl 93, that travels in the groove of a cam 94, on the main shaft. Each revolution of the cam 94, with the main shaft causes the lever 91, to rock and this, through the link 129, and arm 128, rocks the shaft 115. As a consequence the locking bar 117, will disengage from the slots 118, in the L-shaped plates 105, and reengage therewith after the jaws have raised certain of the plates.

Operation: It may be first noted that while I have four different groups (in the present instance) of needles engaging the jacquard card having only three movement needles in each group as in said patent, nevertheless more than one in each or every group may be simultaneously raised by the card, or remain in their lower position because of perforations in the card, according to the selection of movements. But where more than one in a group is simultaneously raised their action is combined through the droppers, so that their combined action causes the selection of a single slide.

A complete operation of the device may be traced as follows: Starting with the parts in the positions shown, the card roller will be moved upwardly, so that the jacquard card will contact with certain of the needles to raise them, while perforations arranged across the card will allow certain of the needles to remain in their lower position. Those needles which are raised will move their respective droppers 29, 30, or 31, as the case may be, into line with the respective rods 34, to 37, through the action of the flexible straps 28. The lever 50, will then be rocked by its operating cam so that the rod 52, and its engaging pins 53, will be moved to the left in Fig. 3. This will allow the levers 39, 40, 41, 42, to be rocked on their shafts by the springs 46, drawing on the several arms 45, and as a consequence they may all move to the left in Fig. 3. But their movements will not necessarily be the same because the rods 34, to 37, will come into contact with the several sets of droppers, and further movement of the levers 39 to 42, will be arrested by such contact. If dropper 29, only is in the path of rod 34, lever 39, will rock to its second position and the pin 61, in the hub of this lever will come into line with the end of slide *g*, of group D. If dropper 30, of the next group is raised into the path of rod 35, by the action of its needle, then lever 40, will rock until rod 35, comes into contact with its dropper 30, which will bring pin 61, of lever 40, into line with slide *f*, of group C. If dropper 31, in the next group is the only one raised, lever 41, will rock until rod 36, comes into contact with said dropper 31, when lever 41, will come to a stop with its pin 61, in line with slide *d*, in group B. If droppers 29, and 30 of the next group are both raised rod 37, will contact therewith and lever 42, will come to rest with its pin 61, in line with slide *e*, of group A. If dropper 30 only in any group is raised such dropper will be moved by the rod into contact with the plate 32, before the lever carrying such rod is arrested and the straps 28, are sufficiently flexible to permit of this movement of the dropper. So also if only dropper 31, of a group is raised it will be moved into

contact with plate 32, before the lever and rod operating against it are arrested. If both 30 and 31 of a group are raised but not 29, then they will be moved until dropper 30, contacts with plate 32, and dropper 31, will lie against dropper 30. It will then be apparent that various movements in the several levers 39 to 42, may be obtained according to the particular droppers in each group which are raised under the action of the jacquard card, and each lever is individually affected according to its particular droppers. If none of the droppers in a group are raised, the rod 34, 35, 36, or 37, as the case may be, will be moved until it comes into contact with plate 32, and will be arrested by the latter, in which position the lever carrying such rod will come to rest with its pin 61, in line with slide *h*, of one of the four groups. Now slide *h*, in any group is not a movement controlling slide as its selection is caused by the failure of a dropper in a group to be raised. Instead slides *h*, operate the devices which lock the rack frames shown in my said patent, and perform the same function as slides *G*⁰⁰, of my said patent, preferably through the rods 7 which correspond with rods *h*⁷ in my said patent, except that when slides *G*⁰⁰ of my said patent remain in their normal position the rack frames are caused to be locked, while in the present device when the slides *H*⁷ are pushed they will cause the rack frames to be locked. The only difference in the mechanism necessary to cause this reversal is the change in the shape of the ends of slides shown in the left of Fig. 1, and in the position of the jaws 113, 114, as previously referred to. Thus if no movement controlling slide in any group is selected for action the locking slide *h* in such group will be operated to lock the particular rack frame which is to be left idle, and the slides *h*, in this action operate through the same locking elements as slides *G*⁰⁰ of said patent.

To revert to the droppers. If dropper 29, in the group shown in Fig. 3, be raised, rod 34, will contact therewith and pin 61, of lever 39, will be in line with slide *g* of group D. If dropper 30, only is raised pin 61, of lever 39, will come into line with slide *f*; if droppers 29, and 30 are both raised, pin 61, will come into line with slide *e* of group D; if dropper 31, only is raised pin 61, will come into line with slide *d*; if droppers 29, and 31, are both raised, pin 61, will come into line with slide *c*; if droppers 30, and 31, are both raised pin 61, will come into line with slide *b*; and if droppers 29, 30, 31, are all raised, pin 61, will come into line with slide *a*. Thus any of the seven movement slides are selected by the use of three droppers and three needles to operate them, and the slide which causes the locking of a rack

frame is selected in case no movement controlling slide in a group is selected. Thus there need be only lateral space on the jacquard card for three needles to operate say 5 seven movement controlling slides. This is the same as to each set of droppers, levers, pins and slides.

The droppers having been raised in the operation assumed and the levers 39, to 42, 10 having been moved to the left in Fig. 3, the levers 67, and the bar 66, carried thereby will be moved laterally of the levers 39, to 42, or toward the slides A. B. C. D. This will cause the reciprocation of all four pins 15 61, in their hubs and their ends will enter the countersunk apertures 63, in the plate 62, with which they aline, and will be guided thereby. Further movement of the pins 61, will cause them to engage the particular slides with which they respectively 20 aline, and cause such slides to be moved to the left in Fig. 1. Through the connecting rods 60 slides in one or more of groups A', B', C', D', etc., with which slides A. B. C. D. 25 are connected will be moved to the left in Fig. 1, but only those connected with those slides A. B. C. D. which were advanced. The slides having been selected and moved, the jaws 113, 114, will be moved toward 30 each other. Those slides which were not moved will be engaged by jaw 114, in the recess 107, and at the top edge 119, by jaw 113, and will be thus held in their lower or normal position and their plates 105 will 35 not operate. But the slides which were advanced will be engaged by the jaw 114, at the point 120, and by jaw 113, in the recess 108, and consequently when the jaws move toward each other, such slides will be raised. 40 As the slides are straddled by the pins 106, their respective plates 105, will be raised and the rods 7, will cause the interlocking of frames 5 and 6 the same as in my said patent. Shaft 115, then rocks and locks the 45 plates 105, whereupon the jaws 113, 114, will be opened again and the slides may be returned to their former position. Shaft 115 will retain the plates locked until just before the jaws close again. The operation 50 and purpose of this is the same as the plate M^o, of my said patent. At the same time, or before, the slides A. B., etc., were moved to the left in Fig. 1, shaft 96, was rocked and moved the bar 97, in the same direction 55 to permit the slides to be so moved. Now that the slides A. have performed their function the plates have been locked and the jaws opened, the shaft 96, will be rocked in a reverse direction by its cam and bar 97 60 will move all slides A. B., etc., which were previously advanced back to their normal or starting position ready for another operation.

In the operation described as soon as the 65 bar 87 has locked the slides (Fig. 1) the

pins 61, and their levers will have completed their operation. Preferably as soon as this has taken place, the lever 67, is rocked back by the cam to withdraw the pins 61, to the position shown in the drawings that is, 70 away from the slides A. B., etc., and out of the apertures 63, of plate 62. As soon as pins 61, are withdrawn the lever 50, is returned by its cam and the pins 53, on the rod 52, will draw all the levers 39, to 42, back 75 or to the right in Fig. 3, and with them the rods 34, to 37, will be moved to their starting position. These levers will now be ready for a second operation. Preferably upon the return of levers 39—42 the card roller 80 10, will be lowered by its operating cam and such droppers and needles as were previously raised will fall back to their lower position to be supported by the plate 27, ready for the next operation. The roller 10, will 85 now be revolved sufficient to bring another transverse row of perforations under the needles ready for a succeeding operation preferably by the mechanism shown in my said patent for revolving the card roller. 90

The direction of the movement to be produced by the rack frame on the planetary gears of my said patent is controlled through needles 22' and their direct connection with slides E. There is a directional needle for 95 each group of movement controlling needles and therefore four in the present showing. If in any group of needles a movement is produced upon an operation of the machine and upon the next successive operation a 100 movement is to be produced in the same direction by the same group of needles, there will be a perforation or blank in the card under the directional needle 22' of such group according to whether there was a perforation or a blank in the previous operation. But if a perforation appeared in the first and not in the second operation a 105 change of direction in a planetary gear occurs; or conversely, if an aperture were 110 present in the second and not in the first a change of direction occurs. If an aperture comes under needle 22' in a group the needle will remain in its lower position when the card is raised and the rod 23, 24, 25, or 26 115 (as the case may be) will remain down; its lever 78, will remain idle and its slide E. will not be moved forward. If no perforation appears under such needle 22'; it will be raised with the jacquard card and through 120 its rod it will rock one of the levers 78. This causes the slides E. with which such lever 78, coöperates to be advanced. As previously stated, the slides E. operate slides I' and the latter preferably are connected 125 with, and operate the same devices as, the slides 1^a, of my said patent, to control the direction of rotation of the planetary gears. The same is true of all the needles 22' and their levers.

In Fig. 8 I have shown a portion of a jacquard card in which I have illustrated a series of perforations sufficient to show how various combinations are effected in one group of needles. The transverse rows are shown separated by dotted lines. The first row 134, will leave all droppers (in the group considered) down and therefore locking slide *h*, will be operated. The second row 135, will cause droppers 30, and 31, to remain down, dropper 29, to raise, and slide *g*, to be selected: row 136, will cause dropper 30, only to be raised, and slide *f*, to be selected: row 137, will cause droppers 29, and 30 to be raised and slide *e*, to be selected; row 138, will cause dropper 31, to be raised and slide *d*, to be selected: row 139 will cause droppers 29, and 31, to be raised: and slide *c* to be selected; row 140 will cause 31 and 30 to be raised and slide *b*, to be selected: and row 141 will cause droppers 29, 30 and 31, to be raised and slide *a*, to be selected.

From the above it will be apparent that the selection of slides is made with fewer jacquard needles than before and in a simple and positive manner.

I prefer to use the form of my invention herein shown because I am thereby able to preserve the advantages of the structure shown in my said patent. I prefer to cause the selection to be made in the slides rather than subsequent mechanisms because the action is simpler and more positive.

I have shown and described my invention in a specific form but I wish it understood that I do not thereby limit my invention thereto, nor limit its application to one form of jacquard.

I have referred to the numbers of parts only to show how my invention may be accurately employed in connection with a jacquard of well known construction from which those skilled in the art may understand the nature and operation of the same.

Having described my invention what I claim is:—

1. A jacquard embodying jacquard selectors, a movable selecting device adapted to select jacquard selectors for operation according to the movements of the selecting device, and members for determining the extent of movement of the selecting device and thereby the selection of the different jacquard selectors.

2. A jacquard embodying jacquard selectors, a movable selecting device adapted to select jacquard selectors for operation according to the movements of the selecting device, and members for determining the extent of movement of the selecting device and thereby the selection of the different jacquard selectors, and jacquard card mechanism operating said members which determine the movement of the selecting device.

3. A jacquard embodying movement controlling jacquard selectors, a movable selecting device adapted to select jacquard selectors for operation according to the movement of the selecting device, members for opposing the movement of the selecting device to cause different jacquard selectors to be selected according to the particular opposing member or members operated, and jacquard card mechanism operating the said opposing members. 70 75

4. A jacquard embodying movement controlling jacquard selectors, a movable and resistible selecting device for selecting the jacquard selectors for operation, and a plurality of members for opposing the movement of the selecting device, adapted to be operated singly or collectively and to cause different movements in the selecting device according to which opposing member or members are operated, and jacquard card mechanism operating said opposing members. 80 85

5. A jacquard embodying movement controlling jacquard selectors, movable and resistible selecting means adapted to select individual jacquard selectors for operation, a plurality of members for opposing the movement of the selecting device to determine the selection of the jacquard selectors and jacquard card mechanism controlling said opposing members. 90 95

6. A jacquard embodying movement controlling jacquard selectors, means for periodically operating said selectors, means for moving said operating means into operative relation with the several selectors, jacquard card mechanism and members operated thereby and adapted to determine the extent of movement of the said operating means and thereby the selector which shall be operated by the periodical operating means. 100 105

7. A jacquard, embodying movement controlling selectors, means for independently operating the selectors and adapted to be placed into operative relation with the several selectors in successive relation, jacquard card mechanism and means operated thereby for controlling the extent of movement of the said operating means and thereby the selection of the different selectors for operation by their said operating means. 110 115

8. A jacquard embodying jacquard selectors for determining the movement to be imparted to a tambour frame, a selecting device for selecting various jacquard selectors to determine which thereof shall be operated, droppers for controlling the operation of the selecting device and jacquard card mechanism operating the droppers to control the selecting device. 120 125

9. A jacquard embodying a plurality of jacquard slides, a selecting device for operating the jacquard slides, jacquard card 130

- mechanism, and elements operated thereby adapted to determine which jacquard slide shall be operated by said selecting device, resistible means for moving the selecting device into operative relation with a jacquard slide according to the operation of the determining elements, and means for periodically and positively returning said selecting device.
10. A jacquard embodying a plurality of jacquard slides, a selecting device for operating the jacquard slides, jacquard card mechanism, and droppers adapted to be operated separately or collectively by the card mechanism, and means for moving the selecting device into operative relation with said jacquard slides according to the operation of the droppers, whereby the said droppers will determine the selection of the jacquard slide to be operated.
11. A jacquard embodying a plurality of jacquard slides, movable and resistible selecting means for operating the jacquard slides, and means for opposing the said selecting means to determine the selection of jacquard slides, and adapted to be operated by a jacquard card mechanism.
12. A jacquard embodying a plurality of jacquard slides, movable and resistible selecting means for operating the jacquard slides and a plurality of elements for opposing the movement of said selecting means to determine the selection of jacquard slides, said opposing elements being adapted to cause different selections according to which opposing element is operated said opposing elements being adapted to be operated by jacquard card mechanism.
13. A jacquard embodying jacquard slides, movable and resistible selecting means for operating the jacquard slides, and a plurality of elements for opposing the movement of said selecting means, adapted to be operated singly or collectively and to cause different selections of jacquard slides according to which opposing element is operated and to cause still other selections when a plurality of opposing elements are collectively operated, said opposing elements being adapted to be operated by jacquard card mechanism.
14. A jacquard embodying jacquard slides, jacquard card mechanism, elements operated by the card mechanism and adapted to individually cause the selection of different jacquard slides and to cause the selection of other of said jacquard slides when two or more of said elements are simultaneously operated.
15. A jacquard embodying jacquard slides, a selecting device for operating the jacquard slides, and means for moving the selecting device successively into operative relation with the several jacquard slides, jacquard card mechanism and elements operated thereby adapted to arrest the said selecting device in operative relation with different jacquard slides.
16. A jacquard embodying jacquard slides, a selecting device for operating the jacquard slides, and means for moving the selecting device successively into operative relation with the several jacquard slides, jacquard card mechanism and elements operated thereby adapted to be independently or collectively operated said elements being adapted to arrest the said selecting device in operative relation with different jacquard slides, the individual arresting elements being adapted to cause the selection of different jacquard slides, and the simultaneous operation of different arresting elements being adapted to cause the selection of other jacquard slides.
17. A jacquard embodying jacquard slides or selectors, means for periodically operating a jacquard slide, means for periodically moving said operating means into operative relation with different jacquard slides, members controlling the extent of movement of said operating means for the purpose of determining the selection of different jacquard slides, said members being adapted to be operated singly or collectively and to cause the selection of different jacquard slides when operated singly, and the selection of other jacquard slides when operated collectively, and jacquard card mechanism for operating said members.
18. A jacquard embodying jacquard slides or selectors, means for operating the jacquard slides, means for moving said operating means into operative relation with different jacquard slides, stationary means for guiding said operating means in its different operative positions relatively to the jacquard slides, and means for controlling the extent of movement of said operating means and thereby determining the selection of particular jacquard slides for operation.
19. A jacquard embodying jacquard slides, a reciprocating element for operating the slides, means for moving said reciprocating element into operative relation with the several slides, a stationary guide having countersunk apertures for guiding said reciprocating element relatively to the several slides, jacquard card mechanism and means operated thereby for determining which jacquard slide shall be operated by the reciprocating operating element.
20. A jacquard embodying a plurality of groups of slides, selecting devices for independently operating slides in the several groups, means for moving the selecting devices into operative relation with the slides of their respective groups, jacquard card mechanism and a plurality of groups of elements operated thereby and adapted to determine the extent of movement of the sev-

eral selecting devices and thereby the slides in the several groups to be operated by their respective operating means.

21. A jacquard embodying a plurality of groups of slides, selecting devices for independently operating slides in the several groups, resistible means for independently moving the selecting devices into operative relation with the several slides of their respective groups, jacquard card mechanism, and groups of elements operated thereby adapted to arrest the several selecting devices in various positions for the purpose of determining which slides in the several groups shall be operated.

22. A jacquard embodying a plurality of groups of slides, rocking means carrying elements for operating the slides in each group of slides independently, means for periodically operating said rocking means to move said slide operating elements into operative relation with the slides in the several groups, means for periodically operating said slide operating elements, jacquard card mechanism, and droppers operated thereby and adapted to determine the positions of said rocking means whereby to cause the selection of any slide in the several groups by their respective operating elements.

23. A jacquard embodying a plurality of groups of slides, rocking members arranged to move across the plane of the several groups of slides, reciprocating pins carried by said rocking members and arranged to operate the slides, a stationary guide between the said pins and slides for guiding the pins in relation to the several slides, dropper engaging elements moving with said rocking elements, springs for independently moving the several rocking members to bring their said pins successively into operative relation with their respective slides, means for periodically releasing and returning said rocking members, means for periodically operating said pins, jacquard card mechanism and groups of droppers operated thereby and adapted to independently arrest the said rocking members whereby the several pins may be caused to operate any of the slides in their respective groups.

24. A jacquard embodying groups of movement controlling slides, locking slides, a selecting device adapted to operate slides in the several groups and to be successively moved into operative relation with the slides

of the several groups, jacquard card mechanism, elements operated thereby adapted to arrest the movement of the selecting device in operative relation with different slides in the several groups, said locking slides being arranged to be operated by the selecting device upon the failure of said card operated elements to arrest a selecting device in operative relation with a movement controlling slide in a group.

25. A jacquard embodying jacquard slides, jacquard card mechanism, and droppers adapted to be separately or collectively operated by the card mechanism and a selecting device adapted to operate the several jacquard slides independently, said droppers being adapted to cause the selection and operation of different jacquard slides when operated individually and to cause the selection and operation of still other jacquard slides when operated collectively.

26. A jacquard embodying movement controlling slides and directional slides, arranged in groups, rocking members carrying slide operating pins adapted to separately operate slides in the several groups, said rocking members being adapted to be moved to bring their respective pins successively into line with the ends of the slides in the respective groups, springs for independently operating said rocking members, a stationary plate having countersunk apertures for guiding said pins in relation to their several slides, rods moving with said rocking members, jacquard card mechanism, and a plurality of groups of droppers operated thereby and arranged to be engaged by said rods to control the movements of said rocking member for the purpose of determining the selection of the several slides to be operated, mechanism for periodically permitting the rocking members to be operated by their springs and to cause the positive return thereof, and means for periodically operating said pins after the positioning thereof according to the operation of the droppers, and adapted to withdraw said pins before the return operation of the rocking members.

Signed at the city, county, and State of New York, this 20th day of November, 1911.

JOSEPH A. GROEBLI.
